WRIST WATCH STRAP

David F. Cowen, New York, N. Y.

Application June 2, 1934, Serial No. 728,668

8 Claims. (Cl. 224—4)

This invention relates to wrist watch straps and particularly to the type wherein a protecting member is interposed between the back of the watch and the wrist of the wearer.

5 My invention contemplates the provision of a two-section strap which is adapted for economical production in large quantities and in which a watch protecting and wrist protecting member is so arranged as to provide a considerable range 10 of adjustment to accommodate the differently spaced ears of different watches whereby the strap may be used with watches of different sizes without detracting from its protective function.

15 My invention further contemplates the provision of a strap in which a pair of relatively movable sections are provided, each section being formed with a pin-receiving loop through which the pin of a wrist watch may be passed, and one of the sections being formed with the watch and 20 wrist protector as a part thereof.

25 My invention further contemplates the provision of strap-holding and watch-holding loops in the strap so arranged and secured as to adequately perform their functions while effecting considerable savings in material and labor, and providing a substantially smooth back on the strap not likely to cause undue pressure on the 30 wrist of the wearer.

The various objects of my invention will be 35 clear from the description which follows, and from the drawing, in which,

Fig. 1 is a perspective view of my improved strap as it appears in its operative position securing a watch to the wrist of the wearer.

35 Fig. 2 is a foreshortened elevational view of the strap, part of one of the loops being broken away to show the underlying stitching, and the watch being shown in dash-dot lines.

40 Fig. 3 is a partial longitudinal section of the same taken on the line 3—3 of Fig. 2.

45 Fig. 4 is a cross-section of the left section of the strap as viewed in Figs. 2 and 3, showing an alternate arrangement of the loop for holding said left section in place.

50 In the practical embodiment of my invention shown by way of illustration, my improved strap comprises two sections, namely, the buckle section 10 and the buckle-tongue-engaging section 11. Each of said sections is preferably made of leather, leather substitute or the like material, and comprises preferably two sheets or layers of material, which I will refer to as the outer and inner layers respectively.

55 Suitable longitudinal stitching as 12 in the buckle section 10 joins the edges of the outer

layer 13 to the inner layer 14. Intermediate its ends, a portion of the outer layer 13 is doubled back on itself to form the watch-pin-receiving loop 15 through which the usual removable pin 16 of the watch 17 may be passed to secure the section 10 to the watch. A transverse line of stitching 18 serves to define the limits of the loop 15 on one side thereof, while a similar transverse line of stitching 19 defines the limit of the loop 15 on the other side. It will be understood, however, that the line of stitching 19 may be dispensed with, by severing the layer 13 just beyond the left edge of the loop 15 as at 20 and tucking the thus severed end of the loop in between the layers 13 and 14 whereupon the stitching 18 alone will secure the parts in place in a manner which will now be obvious, being similar to and sufficiently illustrated by the structure of the loop 26 of the strap section 11, to which further reference will be made hereinafter.

20 I prefer, however, to continue the layer 13 integrally past the loop 15 and there to widen the section 10 to form the outer part of the protecting member or portion 21. At the extreme left end of the member 21, the layers 13 and 14 are 25 slightly separated sufficiently to receive the inner half 22 of the separate band loop 23 therebetween. Said loop half 22 is secured in place between the layers by suitable stitching as 24, while the outer half of the band loop 23 remains spaced outwardly of the member 21 a sufficient distance to 30 permit the insertion thereinto of the strap section 11.

As shown in Fig. 4, however, for the loop 23 may be substituted a similar loop 25, the inner 35 half 44 of which is secured to overlie the inner face of the inner layer 14 by suitable stitching. In any case, the loop 25 or 23 serves to hold the strap section 11 on to the member 21 with the pin-holding loop 26 of said section in position 40 adjustably to engage the pin 27 of the watch.

Said loop 26 is made at the right end of the outer layer 28 of the section 11 by doubling back on itself the end portion 29 of said layer and inserting said end portion, after it has been skived 45 or bevelled, between the layer 28 and the skived end 30 of the inner layer 31. The transverse line of stitching 32 serves to secure together the parts 28, 29 and 31 while the longitudinal stitching similar to the stitching 12 secures the edges of 50 the layers 28 and 31 together.

Suitable means are provided for detachably and adjustably securing the respective free ends of the sections 10 and 11 together to hold the strap on the wrist. Said means may take various 55

forms, but as illustrated, a series of suitable perforations 34 are made in the left end part 35 of the section 11 for the reception of the tongue 36 of a buckle 37 which is secured to the right end 5 38 of the section 10. The usual transverse tongue-carrying pin or cross-bar of the buckle passes through the end loop 39 of the section 10. Said loop 39 is formed by skiving the right end portion of the layer 13, doubling said end portion 10 back on itself, inserting it between the layers 13 and 14 and securing it in place by the transverse stitching 40, in the manner which has been fully described in connection with the loop 26 and the modified form of the loop 15 and hence which 15 requires no detailed illustration.

A pair of separate band loops 41 and 42 are provided on the section 10 for holding the free end 35 of the section 11 in place after the passage thereof through the buckle. The inner half of 20 the loop 41 is secured between the layers 13 and 14 in the same manner as the loop 23 is secured, but the loop 42 encompasses said layers and is free to slide to an adjusted position on the section 10, or may be omitted if desired.

25 It will be noted that the right end of the section 11 is preferably flared or widened to a width slightly greater than the normal of the loop 26, before said loop has been stretched by the passage therethrough of the section 11, so as to prevent its easy passage through said loop and thereby to prevent the section 11 from accidentally being pulled through said loop before the section 30 has been attached to the watch pin 27.

Said flared or widened portion, however, is 35 preferably provided with substantially parallel edges so that the section 11 may be adjusted longitudinally to a considerable extent relatively to the loop 23 and thereby adapt the strap for use in connection with watches in which the distances 40 between the pins 16 and 27 may vary. The left end part of the section 10 may be similarly flared or widened for purposes of symmetry if desired.

To secure the watch and strap together, the pins 16 and 27 of the watch are passed through 45 the respective loops 15 and 26, and the strap tensioned to move the sections 10 and 11 apart so far as the watch pins permit such movement. The member 21 protects the back of the watch from contact with the wrist, a substantially 50 smooth surface being provided on the strap by the inner layers 14 and 31.

It will be seen that I have provided a strap 55 designed to perform its protective and holding functions adequately and effectively, involving the use of minimum amounts of material, adapted to be economically and rapidly manufactured and well designed to meet the requirements of practical use. While I have shown and described certain specific embodiments of my invention, 60 I do not wish to be understood as limiting myself thereto, but intend to claim my invention as broadly as is permitted by the state of the prior art and the scope of the appended claims.

I claim:

65 1. In a wrist watch strap, a first section comprising an inner and an outer layer of material, a watch-pin-receiving loop bent from the end of the outer layer and having the end thereof inserted between said layers and stitched thereto, a second section 70 comprising an inner and an outer layer of material, a watch-pin-receiving loop bent from the outer layer intermediate its ends, a band loop on the end of said second section adjacent the watch-pin-receiving loop 75 of the first section, the inner part of said loop

being inserted between the inner and outer layers of the second section and stitched thereto, a watch protecting portion on the second section between the band loop and the pin-receiving loop, the first section being adapted to be passed through the band loop to arrange the watch-pin-receiving loop of the first section inwardly of the band loop, and cooperating fastening means on said sections. 5

2. In a wrist watch strap, a first section terminating in a watch-pin-receiving loop, a second section provided with a watch-pin-receiving loop intermediate its ends, a fastening element at one end of said second section, that portion of said second section between said loop and the other end of said second section being widened to form a watch protecting member, a band loop on said other end of the second section adapted to have the first section passed therethrough with the watch-pin-receiving loop of the first section 10 arranged inwardly of said band loop whereby said first section is adjustable in the band loop relatively to the second section. 15

3. In a wrist-watch strap, a pair of relatively movable sections, cooperating fastening means on the respective free ends of said sections, means at the other ends of said sections for movably connecting said sections including a band loop, each of said sections comprising an inner and an outer layer of material, a loop bent integrally 20 from the material intermediate the ends of the outer layer of one of said sections, a loop bent integrally from the end of the outer layer of the other section, the end of said last-mentioned loop being skived and inserted between said layers, stitching passing through the layers of said other section and through the skived end and securing the loop in place, and a widened watch-protecting portion on and integral with said one 25 of said sections. 35

4. In a wrist-watch strap, a first section comprising an inner and an outer layer of material and a loop on said section bent from the outer layer and having the end thereof inserted between said layers and stitched thereto, a similar second section having an inner and an outer layer, a widened portion at those ends of the layers of the second section adjacent the loop of the first section, a loop on the second section 45 intermediate its ends, said sections being connectable by a wrist watch having a pair of pins each passed through one of the loops and arranged outwardly of the widened portion. 50

5. In a wrist-watch strap, a first section including an inner and an outer layer of material, a watch-pin-receiving loop bent from the outer layer and having its end inserted between said layers and stitched thereto, a second section 55 comprising an inner and an outer layer of material, a watch-pin-receiving loop bent integrally from the outer layer intermediate its ends, stitching passing through said layers and securing the loop in position, means for slidably connecting said sections at the adjacent ends 60 thereof to arrange said loops in watch-pin-receiving position, a widened watch-protecting member on and integral with said second section between the loops, said loops being each 65 adapted to receive a pin of a wrist-watch to secure the sections adjustable together with the watch overlying the widened member, a buckle on the second section and a perforated end on the first section adapted to enter said buckle to 70

secure the strap in place about the wrist of the wearer.

6. In a wrist-watch strap, a first section perforated at one end and having a watch-pin-receiving loop at its other end, a second section terminating at one end in a band loop, said first section passing through said band loop with the watch-pin-receiving loop arranged inwardly of the band loop, a watch-pin-receiving loop on the second section intermediate its ends, a watch-protecting member on and integral with the second section between the pin-receiving loop and the band loop, and a buckle on the other end of the second section adapted to receive the perforated end of the first section.

7. In a wrist-watch strap, a first section comprising an inner and an outer layer of material, said section being perforated at one end and having a loop formed from the outer layer at the other end, a second section comprising an inner and an outer layer of material, a band loop having part thereof secured at one end of the second section between the inner and outer layers thereof, a second loop on the second section

bent from the outer layer and in spaced relation to the band loop, the first section being adapted to be passed through the band loop to be held frictionally thereby, and the loops of the outer layers being each adapted to receive a pin of a wrist-watch whereby the sections are connected by the watch, and a buckle at the other end of the second section adapted to receive the perforated end of the first section.

8. In a wrist-watch strap, a pair of relatively movable sections each formed of an outer and an inner layer of leather, a widened portion on and integral with one of the sections forming a watch-protecting member thereon, a watch-pin-receiving loop bent from the end of the outer layer of the other of said sections, and a watch-pin receiving loop bent integrally from the outer layer of said one of the sections intermediate the ends of said one of the sections, said loops being each adapted to receive a pin of a wrist-watch to arrange the watch over the watch-protecting member and to hold the sections together.
